UNITED STATES PATENT OFFICE.

BENJAMIN B. BETTS, OF ST. LOUIS, MISSOURI.

RAILWAY-SWITCH.

1,254,304.

Specification of Letters Patent. Patented Jan. 22, 1918.

Application filed December 29, 1916. Serial No. 139,594.

To all whom it may concern:

Be it known that I, BENJAMIN B. BETTS, a citizen of the United States, and resident of St. Louis, State of Missouri, have invented 5 certain new and useful Improvements in Railway-Switches, of which the following is a specification containing a full, clear, and exact description, reference being had to the accompanying drawings, forming a part 10 hereof.

My invention relates to improvements in railway switches and particularly to the construction of the switch point rails and the mountings for the running and switch 15 point rails.

The object of my improvements is to construct the switch point rails and mountings for the running rails and switch point rail which will permit of the bases of the switch 20 point rails being moved laterally over the base flanges of the running rails to the end that a lesser sectional reduction of the switch point rails is obtained and the bases thereof will be co-extensive with their lengths, in 25 order to obtain a maximum of rail body to withstand bending stresses in both lateral and vertical directions caused by rolling stock.

My invention consists in certain novel 30 details of the construction, arrangement and combination of elements which will be fully, clearly and concisely set forth in my specification, pointed out in my claims and illustrated by the accompanying drawings, in 35 which—

Figure 1 shows in plan a fragment of a running rail, a fragment of a siding running rail, a switch point rail embodying my improvements and chairs constructed according to my invention for the support of the 40 switch point rail and the running rails.

Fig. 2 is an enlarged transverse sectional elevation taken on the line 2—2 of Fig. 1.

Fig. 3 is an enlarged transverse sectional 45 elevation taken on the line 3—3 of Fig. 1.

Fig. 4 is an enlarged transverse sectional elevation taken on the line 4—4 of Fig. 1.

Fig. 5 is an enlarged transverse sectional 50 elevation taken on the line 5—5 of Fig. 1.

Fig. 6 is an enlarged transverse sectional elevation taken on the line 6—6 of Fig. 1.

Fig. 7 is an enlarged transverse sectional 55 elevation taken on the line 7—7 of Fig. 1.

Fig. 8 is an enlarged transverse sectional elevation taken on the line 8—8 of Fig. 1.

Fig. 9 is an enlarged transverse sectional elevation taken on the line 9—9 of Fig. 1.

Fig. 10 is an enlarged transverse sectional elevation taken on the line 10—10 of Fig. 1.

Referring to the drawings by numerals 60 11 designates the main running rail, and for purposes of this specification only I will describe the same as being a standard "one hundred pound" rail.

The numeral 12 designates the siding running rail which like the main running rail 11 will also be described as being a standard "one hundred pound" rail.

The numeral 13 designates the switch point rail, which except for its modifications 70 adapting it for use as contemplated by my invention is, for example, a standard "eighty pound" rail.

In rail construction when there is a difference in weight there is a proportional 75 variation in sectional dimensions, hence the running rails 11 and 12, of the one hundred weight have base widths and heights from the bottoms of the bases to the tops of the balls greater than the switch point rail of 80 the eighty pound weight.

In order that the top surface of the switch point rail be maintained in the plane 85 of the top surfaces of the main running rail and siding running rail, I construct a series of chairs provided, each, with seats at different elevations.

The chair 14, shown at the right hand side of Fig. 1 and in Fig. 10 is designed to support the main running rail 11, upon the 90 seat 15, the end of the siding running rail 12 upon the seat 16 and the end or "heel" of the switch point rail 13 upon the seat 17. By reference to Fig. 1 it will be noted the rails 12 and 13 are not parallel with the 95 rail 11, hence the shoulders 18 and overhanging flanges 19, which define the seat 15 for the main running rail are extended at a right angle to the body of the chair while the shoulders 20—20 which define the seat 100 for the end of the siding running rail 12 are extended transversely of the chair body at an angle relative to the shoulder 18 and flange 19 of the seat 15.

The overhanging flange 19 provides means 105 for securing the one base flange of the main running rail to the chair while the other flange is secured by spikes 21, (shown in Fig. 10) extended through openings 22 formed through the chair body intersecting 110

the shoulder 18. The end of the siding running rail is secured by spikes 23 (one only of which is shown in Fig. 10) extended through openings 24 formed through the 5 chair body intersecting the shoulders 20.

It is to be noted that the seat 16 extends for only a portion of the width of the chair and that the seat 17, occupies the remainder of the width of the chair. The seat 17 is 10 defined by oppositely disposed overhanging flanges 25 whose lateral spacing is less than the lateral spacing of the shoulders 20 defining the seat 16, and which flanges serve as rail securing means for the end or heel of the 15 switch point rail.

As clearly shown in Fig. 10 the seats support the ends of the two rails 12 and 13 with their bases in different planes to the end that the tread surfaces of their balls are maintained in like planes. It is to be observed 20 also that the overhanging flanges 25 bear different lateral relationship with the shoulders 20 to the end that the one side surface of the ball of the switch point rail is approximately flush with the corresponding side face of the ball of the siding running rail.

The numeral 26 designates the chair (shown in Fig. 9) next the chair 14 and is 30 arranged to support the running and switch point rails only. This chair has its seats 27 and 28 extending substantially the width of the chair, the seat 27 being in the plane of the body of the chair while the seat 28 occupies a plane above and at one end of the seat 27. The seat 27 is defined at its side next the running rail by a shoulder 29, through which spike openings 30 are formed to receive spikes 31, (one only of which is 40 shown) and at its opposite side (next the switch point rail) by a recess 32 formed in the end of the body of the seat 28.

Arising from the seat 28 and laterally spaced from the recess 32 is a shoulder 33 45 which limits movement of the switch point rail in a direction of the lateral strains incident to traffic, the surface of the seat being otherwise plane to permit free movements of the switch point rail. Extended through the chair at its end opposite the running rail are the openings 34 for the spikes 35 (one only of which is shown) which serve with the spikes 31 to secure the chair in place.

The numerals 36 and 37 designate the 55 chairs next the chair 26, just described and as shown in Figs. 8 and 7 respectively, are identical with the chair 26 except for the locations of their rail-bearing shoulders 38 on the chair 36 and 39 on the chair 37.

60 This difference of location of the shoulders 38 and 39 is occasioned by the difference in the lateral spacings of the switch point rail and the running rail at the points occupied by the two chairs.

65 The numerals 40 and 41 designate the

chairs next the chair 37, and as shown in Figs. 6 and 5 respectively are of identical construction, and differ from the chairs 26, 36 and 37 only by the omission of shoulders on the seats for the switch point rail, hence 70 a detailed description is not deemed necessary.

The numeral 42 designates the chair next the chair 41 and is identical therewith except for the length of its seat, as shown in 75 Fig. 4.

At the point of location of the chair 42 the base flange of the switch point rail is moved in one position to engage the web of the running rail and for this reason the 80 seat is extended to provide a continuous support for the switch point rail to its limit of travel as well as to bring the surface of the seat to approximately flush with the flange of the running rail to obviate pockets that 85 might provide lodgment for foreign matter to the interference in free movements of the base of the switch point rail over the base flange of the running rail.

The numerals 43 and 44 designate the 90 chairs next the chair 42, the chair 44 being the last of the series and arranged for the support of the "point" of the switch rail 13.

The last mentioned chairs are identical with the chair 42 just described except that 95 their bodies are elongated to provide a bearing 45, next their seats for the main running rail, for a rail brace 46, whose base 47 is provided with spike openings whereby it may be secured to the chair. The base 47 100 is provided with a flange 48 which overhangs the base flange, of the running rail, opposite the switch rail to serve as rail securing means. At the end of the chair body there is a shoulder 49 against which the base 47 105 engages and is held against lateral movement, to the end that the brace is maintained in position beneath the ball of the running rail.

It is common in this art to employ a 110 switch point rail of the same weight and sectional dimensions as the running rail, hence in order that the switch point rail may be brought to lie beside the running rail with its ball in position to deflect wheel 115 flanges from the running rail it is necessary to remove the base of the switch rail from its margin next the running rail to a point beneath the web of the switch rail, which results in a sectional reduction leaving too little body at the point of connection between the base and web of the rail and which reduction frequently results in breakage at this point due to lateral bending stresses produced by rolling stock. 120

By providing the chairs as described with seats in different elevations I am enabled to employ a switch rail of lesser sectional dimensions than the running rail and as clearly shown in Figs. 2 to 10 is provided 130

with at least portions of both its base flanges underlying the entire length of the web.

By this arrangement also a great economy is effected in the reduction of a standard rail to adapt it to be employed as a switch point. In this connection it is to be observed that the switch rail for nearly one-half its length is unaltered, while a switch rail of the same weight as the running rail would necessarily have to be sectionally reduced for nearly its entire length.

In Fig. 1 I show a fragment of a switch throwing means, which may be of any approved type and which constitutes with the flanges 25 of the chair at the heel of the rail the sole rail securing means.

Having thus described my invention what I claim is:

1. An improvement in the art of railway switch construction comprising in combination a main rail, a siding rail and a switch point rail of less dimensions than either of the other rails, said switch point rail maintaining throughout its length one base flange and the major portion of the other base flange.

2. An improvement in the art of railway switch construction comprising in combination a main rail, a siding rail and a switch point rail of less dimensions than either of the other rails, said switch point rail maintaining throughout its length one base flange and the major portion of the other base flange, and a rail chair at the junction of the siding and switch point rails having integral means for receiving and securing the heel of the switch point rail.

3. An improvement in the art of railway switch construction comprising in combination a main rail, a siding rail and a switch point rail of less dimensions than either of

the other rails, said switch point rail maintaining throughout its length one base flange and the major portion of the other base flange, and spaced supports along the switch point rail and common to the main rail, having rail seats of different elevations, some of said supports having base flange engaging means to limit the movement of the switch point rail toward the main rail and the remainder of said supports permitting the shaped portion of one of the base flanges of the switch point rail to abut against the web of the main rail.

4. An improvement in the art of railway switch construction comprising in combination, a main rail, a siding rail and a switch point rail of less dimensions than either of the other rails, said switch point rail maintaining throughout its length one base flange and the major portion of the other base flange, and spaced supports along the switch point rail and common to the main rail, having rail seats of different elevations, some of said supports having base flange engaging means to limit the movement of the switch point rail toward the main rail and the remainder of said supports permitting the shaped portion of one of the base flanges of the switch point rail to abut against the web of the main rail, and said supports having undercut recesses for receiving and securing one base flange of the main rail, and rail bearing shoulders for the other flange of the main rail.

In testimony whereof, I have signed my name to this specification, in presence of two subscribing witnesses.

BENJAMIN B. BETTS.
